UNITED STATES PATENT OFFICE

SOPHIE STÉPHANI, NÉE KAUS, OF ZURICH, SWITZERLAND

DESIGN FOR A CASING FOR A MASSAGE APPARATUS WITH HOSE AND CUP ATTACHED

Application filed December 13, 1928. Serial No. 29,249. Term of patent 7 years.

To all whom it may concern:

Be it known that I, SOPHIE STÉPHANI, née KAUS, citizen of Switzerland, residing at Zurich, Hüttensteig 10, Switzerland, have invented a new, original, and ornamental Design for a Casing for a Massage Apparatus, with Hose and Cup Attached, of which the following is a specification.

Reference being had to the accompanying drawings, forming part thereof.

Fig. 1 is a side elevation of a casing for a massage apparatus, with hose and cup attached, showing my new design and

Fig. 2 is an end view of the casing only.

I claim:

The ornamental design for a casing for a massage apparatus, with hose and cup attached, as shown.

In testimony whereof I affix my signature.

SOPHIE STÉPHANI, NÉE KAUS.
